UNITED STATES PATENT OFFICE

154,890

DESIGN FOR A COMBINED BATH ARM AND DETACHABLE CAP

Alfred Walker, North Little Rock, Ark.

Application May 24, 1947, Serial No. 139,265

Term of patent 14 years
(Cl. D9—2)

To all whom it may concern:

Be it known that I, Alfred Walker, a citizen of the United States, residing at North Little Rock, in the county of Pulaski and State of Arkansas, have invented a new, original, and ornamental Design for a Combined Bath Arm and Detachable Cap, of which the following is a specification, reference being had to the accompanying drawing constituting a part thereof.

Fig. 1 is a perspective view of a combined bath arm and detachable cap, showing my new design;

Fig. 2 is a top plan view thereof; and

Fig. 3 is a side view of the left-hand portion of Fig. 1, showing the cap portion separated from the arm.

I claim:

The ornamental design for a combined bath arm and detachable cap, substantially as shown.

ALFRED WALKER.
